UNITED STATES PATENT OFFICE.

IRA M. CLARKE, OF NEW MARTINSVILLE, WEST VIRGINIA, ASSIGNOR TO NEW MARTINSVILLE GLASS MANUFACTURING CO., OF NEW MARTINSVILLE, WEST VIRGINIA, A CORPORATION OF WEST VIRGINIA.

DESIGN FOR A COMBINED HUMIDOR AND ASH TRAY.

Application filed May 31, 1922. Serial No. 2,479. Term of patent 7 years.

To all whom it may concern:

Be it known that I, IRA M. CLARKE, a citizen of the United States, residing at New Martinsville, in the county of Wetzel and State of West Virginia, have invented a new, original, and ornamental Design for Combined Humidor and Ash Tray, of which the following is a specification, reference being had to the accompanying drawing, forming part thereof, in which—

Figure 1 is an elevation of the cigarette,

cigar or tobacco set embodying the present invention.

Figure 2 is a top plan of the same, and Figure 3 is a bottom plan thereof.

I claim:—

The ornamental design for a combined humidor and ash tray, as shown and described.

IRA M. CLARKE.
